FRANKLIN N. CONANT, OF NEWBURYPORT, MASSACHUSETTS, ASSIGNOR TO THE CHASE-SHAWMUT COMPANY, OF NEWBURYPORT, MASSACHUSETTS, A CORPORATION OF MASSACHUSETTS.

RENEWABLE ELECTRIC FUSE AND METHOD OF MAKING IT

Application filed October 31, 1928. Serial No. 316,210.

This invention relates to renewable cartridge type electric fuses of both the knife blade and ferrule terminal type.

A renewable cartridge type electric fuse has a tubular enclosing casing made of insulating material which, usually, is fibre. The insulating tube has screw threads at the ends and metal end caps or ferrules are removably screw-threaded thereon. The material of which the tube is composed, shrinks and swells with variations in atmospheric conditions so that at some times the end caps are tight and at some times the end caps are loose on the casing. A tight end cap is difficult to remove and, if excessive force is applied may damage the fuse. A loose end cap may impair the interrupting capacity of the fuse since it can permit dangerously hot gas to be expelled from the casing when the fuse blows under heavy load. With continued use the threads on the fibre tube wear so that the end cap can not be screwed down tightly. In an attempt to overcome these difficulties, the fibre tubes have been made with heavy screw-threaded metal members at the ends. This construction, however, is not satisfactory because the fibre tube shrinks away from firm engagement with the metal members, so that they are loose on the casing. The construction is also undesirable since the metal members must have thick walls and so the screw-threaded members either must be considerably larger in diameter than the diameter of the insulating tube, so that the metal end caps or ferrules must greatly exceed the diameter of the tube, or the fibre tube must have a thick wall and must be turned down at the ends to receive the heavy screw-threaded members.

An object of the present invention is the provision of a cartridge type fuse having a tubular insulating casing that has screw-threaded end shells that are maintained in firm engagement with the insulating tube at all times regardless of any tendency of the casing to change its dimensions.

A further object of the invention is the provision of a cartridge type fuse having a thin screw threaded metal end ferrule that

is permanently in pressure engagement with the end of the insulating tube.

Another object of the invention is the provision of a renewable cartridge type fuse having a screw-threaded metal ferrule on the end of the enclosing casing and a removable fusible element therefor which is so arranged that it is held in the casing against rotation and also holds the screw-threaded ferrule against rotation.

A further object is the provision of a renewable fuse having an end cap which the a screw-threaded engagement with the tubular insulating casing and wherein means are provided to relieve the casing threads from wear occasioned by the screwing on and off of the end cap.

A further object is generally to improve the construction and operation of removable cartridge type electric fuses.

Fig. 1 is a side elevation of the renewable cartridge type fuse embodying the present invention, with one of the end caps shown in section.

Fig. 2 is a sectional elevation of the fuse of Fig. 1.

Fig. 3 is a view of the left hand end of the fuse of Fig. 1.

Fig. 4 is a view of the right hand end of the fuse of Fig. 1.

Fig. 5 is a perspective view of the removable fusible element of the fuse.

Fig. 6 is a plan detail of the right hand knife blade terminal of Fig. 5, the discs carried by the knife blade being shown in section.

Figs. 7 through 13 are sectional details illustrating progressive steps in the manufacture of the insulating casing and its screw-threaded metal shell.

Fig. 14 is a sectional detail of a renewable electric fuse of the ferrule type embodying the invention.

Fig. 15 is an end view of the enclosing casing of Fig. 14, with the ferrule and end-washer removed.

As here shown, the renewable cartridge type electric fuse embodying the invention comprises a tubular casing 10 composed of insulating material as fibre which is suscepti-

ble to variations in atmospheric conditions and which shrinks and swells accordingly. The casing is provided with screw-threaded metal shells or sheaths 12 at its end, constructed in a manner hereinafter to be described, and metal end caps 14 and 16 respectively which are screw-threaded on said shells and casing to hold the removable unit in place. The tubular casing and the metal shells are made and united in such a manner that the shells are attached rigidly to the ends of the casing at all times and under all usual operating conditions of the fuse and preserve constant dimensions of the screw-threaded portions of the ferrules so that the end caps 14 and 16 fit thereon in the intended manner at all times.

In the manufacture of the fuse, the tubular casing 10 is first run through a die which compresses it and reduces it to a predetermined diameter. Screw-threads 18 are then cut or formed in the periphery of the tube near the ends, and the tube between the screw threads and the ends is turned down to the level of the base of the screw threads thus forming a reduced annular shoulder 20. The casing is then in condition to receive the metal shell. The metal shell or sheath is, at one of the first stages of manufacture thereof, a ferrule of thin ductile metal as indicated in Fig. 8 having a cylindrical or tubular wall 22 and an imperforate end wall 24. The next operation on the ferrule is to form the cylindrical wall 22 with an annular step or neck 26 of reduced diameter which is adapted to fit snugly on the annular shoulder 20 of the insulating casing. External screw threads 28 and corresponding complementary internal screw threads 29 are then formed, by rolling or otherwise, in the cylindrical wall 22; and the end wall 24 is provided with the axial opening 30 as shown in Fig. 10. The internal diameter of the screw-threaded portion of the ferrule is such that it snugly fits the externally screw-threaded end of the casing and is applied thereto as shown in Fig. 11. If found desirable, the shell with the perforated end wall can be applied to the end of the casing and the screw-threads can be rolled therein to conform with the screw threads 28 of the casing. In any event, the construction of the shell and casing is such that the shell fits tightly on the casing. A tapered expanding tool A, Fig. 11, is then forced in the opening 30 in the end wall of the shell, thereby to force the end wall 24 inwardly of the tubular casing and to convert the wall to an annular flange and to compress the flange firmly and permanently against the inner face of the casing. In this manner the end of the casing is compressed between the inner and outer annular sections 26 and 24 respectively of the shell and is held permanently in this relation and thus is prevented from shrinking

and swelling. Consequently, the metal shell tightly grips and is held firmly on the end of the casing. The annular section 26 of the shell is punched at various localities to provide spurs 32, Figs. 1 and 13, which are embedded in the annular section 20 of the casing and thus positively lock the shell against rotation. The metal wall 22 of the ferrule is so thin that it does not materially increase the diameter of the insulating casing thereat and also is so thin that the cap threads can mesh with the casing threads, as is clear from an inspection of Fig. 13, so that the casing threads hold the end cap from axial displacement on the casing and the metal ferrule takes the wear that otherwise would materially fall on the easily-worn casing threads. The casing at one end is provided with diametrically-opposed notches 34 which extend axially through the annular shoulder 20 of the casing and also through the inner and outer sections 24 and 26 of one of the shells. The functions of these slots is to hold the removable fuse unit in place against rotation.

The removable fuse unit for the fuse illustrated in Figs. 1 and 2 consists of an insulating bar 36 to the ends of which knife blade terminals 38 and 40 are rigidly secured. A fusible link 42 is removably connected with the inner ends of the knife blade terminals by means including clamping screws 44. The knife blade 40 is provided with means by which the removable unit is locked to the enclosing casing against rotation. To this end, the inner end 40a of the knife blade terminal is made narrower than the outer end and discs 48, 50 and 52 are secured thereon between the shoulder 54 of the wide part of the knife blade terminal and projections 56 of the narrow part of the terminal. The disc 52 is adapted to be seated upon the right hand end of the enclosing casing and against the metal ferrule 12 thereon. The end cap 16 has an annular hole 58 in its end wall 60 in which the knife blade terminal is located and the end wall is adapted to bear against said disc 52 whereby to clamp it against the end of the casing and to secure the removable unit within the enclosing casing. The discs 48 and 50 are adapted to fit within the enclosing casing and to engage the inner face thereof whereby to hold the removable unit centrally within the casing. The disc 50 is provided with a pair of diametrically-opposed outstanding lugs or projections 62 which are located within the slots 34 of the right hand end of the casing whereby to hold the removable unit against rotation. The lugs engage both the edges of the screw-threaded shell and the edges of the enclosing casing at said slots and thus positively lock the shell against rotation on the casing at the time the end cap 16 is turned. The discs 48 and 50 are provided with axially disposed grooves 64

in their peripheries which register with grooves 66 formed in the inner face of the disc 52 and which extend to the outer periphery of said disc for the purpose of providing gas vents from the interior of the casing into the end cap. The knife blade terminal 38 has secured thereto discs 68 which closely fit within the casing at the other end thereof. The end cap 14 is provided with a slot 70 in its end wall 72 through which the knife blade terminal 38 is extended.

In assembling the fuse the cap 14 is first screwed on the metal shell at one end of the casing and is located so that the slot 70 therein is in line with the slots 34 at the other end of the casing. The removable unit is then inserted in the casing with the knife blade 38 extended through the slot 70 in the end cap 14. The other end cap 16 is then screw-threaded on the shell to lock the removable unit in place.

Fig. 14 illustrates a ferrule type renewable fuse having the metal shell 12 as above described applied to the end of the enclosing casing. In this construction diametrically opposed notches 74 are formed in the ends of the metal shell and the enclosing casing and the inwardly extended lugs 76 of a fuse link supporting disc 78 are extended into said notches for the purpose of holding said disc against the end of the casing and against rotation. The renewable fuse strip 42a is extended through a slot in said disc and the end 42b thereof is placed over the outer face 30 of said disc. A metal ferrule 80 is screwed onto the metal shell to compress the end of the fuse strip between it and the disc 78 and also to clamp the disc onto the end of the casing. The construction of the insulating casing and the metal shell of this modification is the same as above described in connection with the knife blade fuse.

I claim:

1. In a renewable electric fuse, a tubular enclosing casing of insulating material having an end part of the same diameter provided with external screw threads, and a thin ductile metal shell provided with complementary internal and external rolled screw threads and which engages both the outer screw-threaded and inner faces of said casing and has opposed, thread-free inner and outer annular sections that are smaller in diameter than the diameter of the screw-threaded portion of the casing and that have been flexed into permanent pressure applying engagement with the end of said casing on the inside and also on the outside thereof.

2. In a renewable electric fuse, a tubular enclosing casing of insulating material having external screw threads and a thin ductile metal shell having rolled complementary internal and external screw threads received on said casing screw threads and having spaced internal and external annular flanges between

which the end of said casing is compressed, both flanges being free from threads and said outer flange having an internal diameter that is less than the diameter of said screw threaded portion of said casing.

3. In a renewable electric fuse of the cartridge type, a tubular enclosing casing of insulating material having external screw threads at one end, a thin ductile metal shell, having both rolled internal and external screw threads which are complementary, the internal screw threads engaging the screw threads of said casing, said shell having an annular thread-free outer portion of lesser diameter than the screw-threaded portion and lying between said portion and the end of the casing and also having the end portion thereof beyond said annular portion reflexed over the end of said casing and inwardly thereof and provided within said casing with an annular flange which is expanded against the inner face of said casing, the shell being so thin that it does not materially change either the external or the internal diameter of the casing.

4. In a renewable electric fuse of the cartridge type, a tubular enclosing casing of insulating material having external screw threads at one end, a metal shell having both internal and external screw threads, the internal screw threads engaging the screw threads of said casing, said shell having the end portion thereof reflexed over the end of said casing and inwardly thereof and provided within said casing with an annular flange which is expanded against the inner face of said casing, said shell and said casing having registering notches in the ends thereof.

5. In a renewable electric fuse, a tubular enclosing casing of insulating material having external screw threads and a reduced thread-free annular section between said screw threads and the end of said casing, and a thin metal shell having corresponding internal and external screw threads received on the screw threads of said shell and having a reduced thread-free annular section received on said reduced annular section of said casing and having a part that is reflexed over the end of said casing into the interior thereof and having within said casing an annular flange that is compressed against the inner face of said casing.

6. In a renewable electric fuse, a tubular enclosing casing of insulating material having external screw threads and a reduced thread-free annular section between said screw threads and the end of said casing, and a thin ductile metal shell having corresponding rolled internal and external screw threads received on the screw threads of said shell and having a reduced thread-free annular section received on said reduced annular section of said casing and having a part that is reflexed over the end of said cas-

ing into the interior thereof and having within said casing an annular flange that is compressed against the inner face of said casing, said fuse having a notch in the end thereof, 5 of which is located in the end of said casing and also in said annular flange.

7. A renewable electric fuse including the combination of a tubular enclosing casing of insulating material having external screw 10 threads at an end thereof, a metal shell having both internal and external screw threads screw-threaded onto the screw threads of said casing, said shell having an end thereof reflexed over the end of said casing and into 15 the interior of said casing and forcibly against the inner face of said casing, said fuse having a notch therein which is formed in said shell and also in the end of said casing, a fuse-holding member located at the end 20 of said casing and shell having a projection which is located in said notches and engages both said casing and said shell and holds said shell against rotation on said casing, and an internally screw-threaded end cap which is 25 screw-threaded on said shell and holds said member in the aforesaid relation.

8. In a renewable electric fuse, the combination of a tubular insulating casing having a notch in the end thereof, a metal ferrule 30 on the end of said casing having a notch which is in register with the casing notch, and means to hold said ferrule and casing against relative rotation including means which is located in both notches, and is re- 35 movable from said notches by movement axially of said casing.

9. In a renewable electric fuse, the combination of a tubular insulating casing having a notch in the end thereof, a metal ferrule 40 on the end of said casing having a notch which is in register with the casing notch, and means to hold said ferrule and casing against relative rotation including means which is located in both notches and is removable from 45 said notches by movement axially of said casing, and means which retains said last-named means in said notches.

10. In a renewable electric fuse, the combination of a tubular insulating casing having 50 a notch in the end thereof, a metal ferrule on the end of said casing having a notch which is in register with the casing notch, a fusible element in said casing, and means to

hold said ferrule and casing against relative rotation including a supporting member for said fusible element having a part which is located in both notches.

11. In a renewable electric fuse, the combination of a tubular insulating casing having a notch in the end thereof, a metal ferrule on the end of said casing having a notch which is in register with the casing notch, a fusible element in said casing, and means to hold said ferrule and casing against relative rotation including a supporting member for said fusible element having a part which is located in both notches, and means which retains said member in said notches. 70

12. In a renewable electric fuse, the combination of an externally screw threaded tubular insulating casing having a notch in the end thereof, a metal ferrule screw threaded on the end of said casing and having external screw threads and a notch which is in register with the casing notch, and means to hold said ferrule against rotation on the casing threads including a member which is located in both notches. 80

13. In a renewable electric fuse, the combination of an externally screw threaded tubular insulating casing having a notch in the end thereof, a metal ferrule screw threaded on the end of said casing and having external screw threads and a notch which is in register with the casing notch, and means to hold said ferrule against rotation on the casing threads including a member which is located in both notches, and an end cap screw threaded on said ferrule and which holds said member in said notch. 90

14. In a renewable electric fuse, the combination of an externally screw threaded tubular insulating casing having a notch in the end thereof, a metal ferrule screw threaded on the end of said casing and having external screw threads and a notch which is in register with the casing notch, a fusible element located in said casing, a supporting member for said element having a part which is located in both of said notches and which holds said ferrule against rotation on the casing threads, and an end cap screw threaded on said ferrule and which retains said supporting member in the aforesaid relation. 100
